UNITED STATES PATENT OFFICE.

HERMAN C. PFEIL, OF CAMDEN, NEW JERSEY, ASSIGNOR TO JACOB BUFF,
OF PHILADELPHIA, PENNSYLVANIA.

PRINTER'S BLANKET.

SPECIFICATION forming part of Letters Patent No. 364,287, dated June 7, 1887.

Application filed July 24, 1886. Serial No. 202,956. (No model.)

To all whom it may concern:

Be it known that I, HERMAN C. PFEIL, a citizen of the United States, residing at Camden, in the county of Camden and State of New Jersey, have invented certain new and useful Improvements in Printers' Blankets, of which the following is a specification, reference being had therein to the accompanying drawings.

The object of my invention is to provide a printer's blanket which will be less expensive and equally as durable as the rubber blanket now in use, and which, being perfectly non-elastic, will avoid the stretching of the paper during the process of printing, and which will avoid the suction between the paper and the blanket which occurs when the ordinary rubber printing-blanket is used, and which is very objectionable.

My invention consists of a blanket formed of a sheet of Manila paper and a sheet of oil-cloth, or of a sheet of Manila paper placed between two sheets of oil-cloth.

In the drawings, Figure 1 is a plan of a blanket consisting of two strips of oil-cloth with a strip of Manila paper secured to and between them, the several sheets or strips be-

ing broken away to show the ones beneath them; and Fig. 2 is a section of the same on line *x x*.

A A' are strips of oil-cloth, to and between which is secured, by any suitable means, the Manila paper B.

In the drawings two strips of oil-cloth are shown, and in this arrangement either side of the blanket may be used; but, if desired, only one strip of oil-cloth backed by Manila paper or some other suitable non-elastic substance may be used.

Having thus described my invention, I claim—

A printer's blanket consisting of a strip or strips of oil-cloth, and a strip of Manila paper, or other suitable non-elastic material, secured together substantially as and for the purposes set forth.

In testimony whereof I affix my signature in the presence of two witnesses.

HERMAN C. PFEIL.

Witnesses.
